GORDON E. ROEDDING, OF GRAND RAPIDS, MICHIGAN, ASSIGNOR TO GRAND RAPIDS
BRASS COMPANY, OF GRAND RAPIDS, MICHIGAN, A CORPORATION OF MICHIGAN.

FURNITURE FIXTURE.

Application filed November 3, 1926. Serial No. 145,939.

The present invention relates to fixtures or fittings adapted for mounting on articles of furniture and the like, particularly such fixtures as hinges, locks, latches, etc.; and its object is to provide such fixtures so formed as to not mar or deface the surface of the articles whereon they are mounted.

This object is attained by, and the invention finds embodiment in, the fixture or fitting hereinafter particularly described in the body of this specification and illustrated by the accompanying drawings, in which:—

Figure 1 is a face view of a hinge mounted on the body of a refrigerator and carrying the closure of its door opening;

Figure 2 is a horizontal sectional view of said parts taken on line 2—2 of Figure 1; and

Figure 3 is a vertical sectional view thereof taken on line 3—3 of Figure 1.

When metallic fixtures or fittings, such as hinges, locks, latches, etc., are mounted on the varnished, enameled, polished or otherwise high "finished" surface of a base, as an article of furniture or the like, the edges of such a fixture when the same is forced into tight contact with such a surface in the process of mounting of the fixture thereon, are liable to visibly mark, or otherwise mar or deface such surface. The object of the present invention is to obviate this difficulty.

In the accompanying drawings, a hinge fixture is shown as one embodiment of the invention, the same having the leaf 1 secured by screws 2 to a base—the body 3 of a refrigerator or the like—, and the leaf 4 secured by screws 5 to a base—the closure 6 for the refrigerator's door opening—, said leaves being connected by the pintle 7.

At least one of these leaves of said hinge— as leaf 4 illustrated cross-sectionally in Figure 3—comprises a body portion 8, an edge portion 9 having an edge or extremity 10, and a portion 11 intermediate said edge and the body portion 8. This body portion is spaced outwardly from the base (the closure 6) and the edge portion 9, nearly parallel with said body portion, is also spaced slightly

outwardly from said base as seen at 12. The intermediate portion 11 which forms a flange of the body portion has a convexly curved 50 outer surface 13 which contacts the surface of the base in the mounted position of the fixture thereon.

It will be seen that when the screws 5 are turned down to bring the leaf 4 into tight 55 contact with the surface of the base 6, the convexly curved surface 13 of the fixture, when forced on the base, will not mark or mar the same; or in case of any slight marking or marring thereof, the same cannot be seen in- 60asmuch as the edge portion 9 of the fixture extends outwardly far enough to cover and conceal the contacting point of the fixture with the base 6.

In the views, the base 6 is shown covered 65 by a metallic finishing sheet 14 overlying the wooden understructure 15 of the base. It is particularly necessary that such metallic surfaces of bases as are provided by such metallic and highly finished sheets 14 be protected 70 from the defacing or marring action of fixtures mounted thereon.

Although I have shown only one form of a fixture embodying my invention, it is evident that the same may be embodied in many 75 other fixtures having essentially the same structure as that shown in the leaf 4 of the illustrated hinge.

I claim:

A fixture adapted to be mounted on a 80 frangible base and comprising a portion contacting the base and a marginal edge portion extending outwardly from said contacting portion a sufficient distance and at such a slight acute angle relatively to the base as to 85 conceal from view the contacting point of the first-mentioned portion with the base, whereby mars made on the base by said contacting portion are not visible.

In testimony whereof I have hereunto set 90 my hand at Grand Rapids, Michigan, this 25th day of October, 1926.

GORDON E. ROEDDING.
